UNITED STATES PATENT OFFICE.

EMIL EINFELDT, OF DAVENPORT, IOWA, ASSIGNOR TO BETTENDORF METAL WHEEL COMPANY, A CORPORATION OF ILLINOIS.

MACHINE FOR FORMING SPOKE-HOLES IN HUBS.

SPECIFICATION forming part of Letters Patent No. 690,906, dated January 7, 1902.

Application filed August 28, 1901. Serial No. 73,603. (No model.)

To all whom it may concern:

Be it known that I, EMIL EINFELDT, of Davenport, county of Scott, and State of Iowa, have invented a new and useful Improvement in Machines for Forming Spoke-Holes in Hubs, of which the following is a specification.

This invention relates to a machine for forming spoke-holes in wheel-hubs, and has reference more particularly to means for holding the hub in predetermined positions to receive the holes at predetermined points and in two rows for staggered spokes.

The invention consists, primarily, of a device adapted to hold the hub temporarily in predetermined positions to receive one row of holes and so formed that by the reversal of the hub end for end it will be held in such predetermined positions with relation to the hole-forming device that the holes of the second row will be formed opposite the intervals between the holes of the previously-formed row.

The invention consists also in the details of construction and combination of parts hereinafter described and claimed.

In the accompanying drawings, Figure 1 is a side elevation of my improved machine, showing the hub in place to be acted on by the punch. Fig. 2 is a top plan view with the punch omitted to expose the other parts to view. Fig. 3 is a front elevation of the machine. Fig. 4 is a diagrammatic view showing how by the reversal of the hub the second series of holes will alternate with the first series.

Referring to the drawings, the machine comprises a hole-forming device in the form of a vertically-movable punch 1 and a hub-holding device in the form of a core 2, adapted to extend within the hub and present the same beneath the punch, as shown in Fig. 1. These parts are mounted in a frame 3, having an overhanging portion in which the punch is mounted to reciprocate vertically, and an underlying horizontal bed portion which gives support to the hub-holding device.

The hub-holding core is formed on the inner end of a horizontal stem 3^x, mounted to rotate in a frame 4, which frame is mounted slidingly on two horizontal guide-rods 5, projecting outward from the main frame, the

arrangement being such that the sliding frame may be moved out on its guide-rods to permit the hub to be slipped on the core and then 51 inward to bring the hub beneath the punch.

The hub-holding core is formed to be detachably engaged with the hub, to the end that they will for the time being be held in fixed relations, and the core is adapted when 60 thus engaged with the hub to be rotated step by step to successively present the hub at predetermined points beneath the punch, means being provided for determining or governing the rotary movement of the hub to control the 65 intervals between the holes. The construction of the parts to effect these results may be varied; but I prefer that shown in the drawings, in which the core is provided with a laterally-projecting pin 6, adapted to enter a hole formed in the hub about midway between its ends. The relative size of the core is such that the pin may be readily engaged or disengaged in the hole by a lateral movement of the hub with relation to the core. 75

At the outer side of the sliding frame the stem 3 has fixed to it a wheel 7, having in its periphery a series of teeth 8, spaced apart a distance corresponding to the distance between the holes to be formed in the hub, a 80 pawl 9 being mounted on the frame in position to engage between the teeth and hold the wheel temporarily in its predetermined positions. This pawl is limited in its movement in one direction—that opposite the direction of rotation of the wheel—by a stop 10, so that while the pawl will yield to permit the wheel to be advanced in one direction it will hold the wheel against return movement, the result being that the core, by means of the 85 wheel and pawl, may be advanced accurately step by step the same distance each time and held between each movement. On the outer end of the stem is a handle in the form of a knob 11, by which it may be turned and held 95 by the hand.

Vertically beneath the punch 1 is arranged a fixed anvil 12, which is adapted to extend within the end of the hub when the latter is moved up to the position for punching, and it serves to give support to the hub at the point where the punch enters the same. 100

In the operation of the mechanism to form the rows of holes in the hub the operator

grasps the knob 11 and slides the frame outward to give room for the hub to be set in place on the core. The hub is slipped over the end of the core and the pin 6 entered in the central hole in the hub. The frame is now pushed forward on its guides, the end of the hub being passed over the anvil beneath the punch. The latter descends and forms a hole in the hub, after which it ascends, and 5

10 while free of the hub the operator by means of the knob 11 rotates the toothed wheel one tooth, the pawl yielding and dropping back in place behind the next tooth and holding the wheel in this position. The punch again de-

15 scends and forms a second hole, spaced from the first hole a distance equal to that between the first and second teeth on the wheel, and so on, these operations being repeated until the entire row of holes, accurately spaced, 20

20 has been formed in one end of the hub. After this operation the operator again slides the frame outward, disengages the hub from the pin on the core, and reverses the same end for end, again inserting the pin in the hole in

25 the hub for the purpose of punching the holes in the other end of the hub to receive the second row of spokes for staggered wheels. In wheels of this character the spokes at one end are set in the intervals between the spokes at

30 the opposite end of the hub, and in order that when the hub is reversed in the machine on the core, as just described, the second row of holes will thus alternate with the first row I so form the parts with relation to each other

35 that when the hub is presented in its reversed position to the punch it will be so disposed that the holes formed by the punch will alternate with those of the row previously formed. I accomplish this result by so forming and ar-

40 ranging the teeth on the wheel with relation to the pawl, to the pin 6, and the punch that the pin when the pawl is holding the wheel by engaging between the teeth thereon will be to one side of a line extending longitudi-

45 nally of the core and touching the punch, as illustrated in the diagrammatic view, Fig. 4. As a result of this arrangement the reversal of the hub on the core shifts the previously-formed hole to one side with relation to the punch, and consequently presents surfaces beneath the punch which will be opposite the spaces between the holes of the first row.

It is important that the degree of "offset" 50 of the pin be just half the distance between the holes; otherwise if the offset to one side were equal the distance between the holes the holes of the second row formed on the reversal of the hub would be directly opposite the holes of the first row.

55 60 Having thus described my invention, what I claim is—

1. In combination with a hole-forming tool,

a hub-holding device adapted to be detachably engaged with the hub and present the same in reverse positions to the tool to receive holes at predetermined points, the relation of the tool and engaging means being such that the holes formed in one end will be opposite the intervals between the holes in the other end. 65

70 2. The combination with a hole-forming tool, of a hub-holding device adapted to present the hub in predetermined positions with relation to the tool, and means for engaging the holding device with the hub in reverse 75 positions; whereby both ends of the hub may be presented to the tool.

3. In combination with an operating-tool, a hub-holding device adapted to present the hub in predetermined positions to the tool and 80 means for engaging the hub with the holding device in reverse positions, said means being so formed with relation to the tool that the holes formed in the two ends of the hub will alternate with each other. 85

4. In combination with a hole-forming device, an anvil fixed beneath the same, a rotating core adapted to enter one end of a hub and movable to and from the anvil; whereby the opposite end of the hub may be presented 90 over the anvil to the action of the tool.

5. In combination with an operating-tool, a hub-holder comprising a rotary device adapted to enter the hub, means for engaging the device with the hub in reverse positions and 95 means for determining the movement of the device to advance the hub step by step.

6. In combination with a hole-forming tool, a rotary core adapted to extend within the hub and provided with a pin arranged to enter a hole in the hub; whereby the hub may be reversed end for end on the core, and means for determining the movement of the core to present the hub to the tool in predetermined positions. 100

7. In combination with an operating-tool, a rotary core provided with a pin arranged to one side of a longitudinal plane through the core and tool. 105

8. In combination with a hole-forming tool, a slide movable to and from the same, a rotary hub-holder carried by the slide and adapted to engage and present a hub to the action of the tool, and means for rotating the hub-holder to present the hub at predetermined 110 positions with reference to the tool. 115

In testimony whereof I hereunto set my hand, this 17th day of June, 1901, in the presence of two attesting witnesses.

EMIL EINFELDT.
